UNITED STATES PATENT OFFICE.

HARRY W. HESS, OF PROVIDENCE, RHODE ISLAND.

LENS.

1,258,006.

Specification of Letters Patent.

Patented Mar. 5, 1918.

Application filed June 29, 1917. Serial No. 177,790.

To all whom it may concern:

Be it known that I, HARRY W. HESS, citizen of the United States, and resident of Providence, R. I., have invented certain new and useful Improvements in Lenses, of which the following is a specification.

This invention relates to lenses for the transmission and refraction of light rays and is intended to provide a lens for such purpose which shall produce the most efficient results by blending as uniformly as possible the transmitted light rays over the area that is required to be illuminated. Such lenses may be effectively used for motor car head-lights, search lights, and other purposes and serve to afford efficient illumination while reducing intensity of the glare.

The invention essentially comprises a main body or disk provided with rows of convex bosses or projections on one face in closely arranged series whose individual convex elements progressively decrease in height and diameter from the peripheral portion to the center of the disk as will be more particularly explained hereinafter.

Referring to the drawings in which I have illustrated concrete applications of the principles of this invention,

30 Figure 1 is an elevation or front view of one form of the lens.

Fig. 2 is a section thereof extending from the periphery to the center on the plane indicated by dotted line X.

35 Fig. 3 is an elevation or front view of a portion of a lens having a slightly modified arrangement of the convex refracting elements, in which the radial series of elements are arranged on straight radial lines.

40 In the practice of this invention according to the form illustrated in Fig. 1 the disk *a* of glass or other translucent material is formed with one plane surface as indicated at *a'* while on the opposite side are formed

45 a series of closely arranged convex elements which in this case are arranged in series forming radial curves from the center to the periphery as indicated by dotted line X in Fig. 1. It will also be noticed by reference

50 to dotted line *y* on Fig. 1 that the arrangement of elements in this case is such that they form radiating curves in opposite directions the curves in one direction having a different modulus of curvature from those

65 in the other direction. In this case both

curves are in the form of logarithmic spirals which arrangement makes possible a greater number of different sizes of individual elements, the sizes progressively decreasing from the periphery to the center by a pre-determined ratio and giving a maximum amount of refraction to the light rays passing through the entire lens.

The convex elements *b* are preferably circular in cross-sectional planes intersecting their individual axes at right angles or parallel to the rear face *a'* of the lens.

The profile curvature of each individual element may be varied according to the particular requirements of service for which the lens is intended. If the curvature or contour of each element in a plane intersecting its central axis or, in other words, at right angles to the rear face of the lens be of parabolic form there will be a greater concentration of the light rays passing through the central or apex portion of each convex element than if the elements be given a curvature or contour of more nearly circular form.

While I prefer, generally speaking, to use an arrangement of the light refracting bosses similar to that shown in Fig. 1, in which they form oppositely curved series radiating from the center, nevertheless these elements may be arranged as shown in Fig. 3 with each radiating series extending in straight lines from center to circumference. This arrangement, however, involves a greater ratio of reduction in size for each successive element in the series extending from the circumference to the center while the arrangement of radiating curves makes it possible to progressively reduce the size of each successive element in the series by a smaller ratio of difference.

The resultant effect particularly where elements of the parabolic contour or convex curvature are employed is a diffusion of a portion of the rays with a forward projection of the strongest rays passing through the apex or central portions of the refracting elements, thereby greatly reducing the dazzling or glare effect of the transmitted lights while affording abundant and strong illumination. The close order or arrangement of the refracting elements enables them to act with maximum obtainable effect on the entire body of light rays passing through the lens.

What I claim is:

1. A light transmitting lens embracing in its construction a disk of translucent material provided on one face with closely arranged series of convex bosses of circular contour, the individual bosses gradually increasing in size from center to circumference and being arranged in oppositely curved radiating spirals, substantially as described.
2. A light transmitting lens embracing in its construction a disk of translucent material provided on one face with closely arranged bosses gradually increasing in size from center to circumference and arranged in oppositely curved radiating spiral rows

of unequal length and curvature, substantially as described.

3. A light transmitting lens embracing in its construction a disk of translucent material one side of which is a plane surface, the opposite side being formed with closely arranged series of convex bosses of circular form and having a parabolic cross sectional contour, said bosses gradually increasing in size from center to circumference and arranged in oppositely curved radiating spiral rows, substantially as described.

In witness whereof, I have subscribed the above specification.

HARRY W. HESS.
